ARVID PAULUS PAULSSON, OF DELSBO, SWEDEN.

METHOD OF MANUFACTURING SINKING-WEIGHTS FOR FISHING-TACKLE.

1,050,748.

Specification of Letters Patent. Patented Jan. 14, 1913.

Application filed May 4, 1911. Serial No. 625,080.

To all whom it may concern:

Be it known that I, ARVID PAULUS PAULSSON, a subject of the King of Sweden, residing at Delsbo, in the Kingdom of Sweden, 5 have invented a Method of Manufacturing Sinking-Weights for Fishing-Tackle, of which the following is a specification.

My invention relates to fishing tackle sinkers comprising connected weights.

10 In my improvements a wire is weakened, as by incisions or indentations, at suitable intervals, a tubular fabric is woven thereon, and the sections of wire separated at the incisions or indentations, producing a flexible 15 sinker continuously weighted throughout its length, having a uniform thickness, and a comparatively small diameter for a comparatively great weight by reason of the continuous arrangement and character of 20 the weights. In practice, the wire used is preferably a heavy material of low tensile strength, such as lead, and it is incised or indented so that it can be separated into independent sections at the desired intervals 25 by any usual means, such as rotary star wheels or toothed drums. The incised wire, which has sufficient strength to permit it to be handled in the covering operation, has a fabric woven or plaited thereon so as to hold 30 the sections of wire together when such sections have been separated. The wire having been covered, the sections are separated, which can be effected by passing it between three or more cylindrical rods arranged so 35 that such covered wire will be carried in a zig-zag path and broken at the incisions or places of least resistance.

The accompanying drawings illustrate successive steps in the process of manufacturing my improved sinker and the finished article.

Figure 1 is a side elevation of a section of lead wire; Fig. 2 is a side elevation of the same after it has been subjected to the incising or indenting operation; Fig. 3 is a side

50 elevation of the indented wire section representing the character of the fabric woven thereon, part of the fabric being broken away to illustrate the character of the section covered thereby; and Fig. 4 is a side elevation of a section of the finished sinker, part of the covering being removed to show the interior construction.

Referring to the drawings, the lead wire *a* is provided with the incisions or indentations *b* forming the sections *a'*, the wire thus indented has the woven tube *c* placed thereon, and the sections of the covered wire are separated by breaking them apart on the lines *d*. There is thus formed a sinker that 60 is flexible, substantially uniform in character, continuously weighted throughout its length and therefore comparatively small in diameter for a given weight required.

Having described my invention, I claim: 65

1. The method of manufacturing sinkers for fishing tackle which consists in forming a series of incisions in a wire of heavy material, providing the incised wire with a covering fabric and separating said wire by 70 breaking it in the sections incised.

2. The method of manufacturing sinkers for fishing tackle which consists in forming a series of cuts at predetermined intervals in a wire of heavy material, weaving a covering on said wire, and breaking said wire at 75 the cuts.

3. The method of manufacturing sinkers for fishing tackle which consists in weakening at intervals a wire of heavy material 80 so as to provide readily separable sections, covering said wire so as to connect said sections, and breaking said sections apart by bending said wire.

In testimony whereof I have affixed my 85 signature in presence of two witnesses.

ARVID PAULUS PAULSSON.
